Ralph E. Wilder:
Geo. E. Thackray
his ATTORNEY

UNITED STATES PATENT OFFICE.

RALPH E. WILDER, OF JOHNSTOWN, PENNSYLVANIA.

CAR-TRUCK.

1,208,871.

Specification of Letters Patent. Patented Dec. 19, 1916.

Application filed October 25, 1916. Serial No. 127,509.

To all whom it may concern:

Be it known that I, RALPH E. WILDER, a citizen of the United States, residing in the city of Johnstown, in the county of Cambria and State of Pennsylvania, have invented certain new and useful Improvements in Car-Trucks; and I do hereby declare the following to be a full, clear, and exact description of the invention, such as will enable others skilled in the art to which it appertains to make and use the same.

My invention relates to car trucks with particular reference to those adapted for supporting heavy cars, and to the construction of the truck columns which I make of pressed steel, of shapes such as to well resist the stresses to which they will be subjected, and formed integrally therewith is an inwardly extending portion adapted to directly receive the brake beam stirrup or hanger, thus simplifying the construction and reducing the number of parts thereof. I also provide a reinforcement for the lower portion of the arch bar or similar member, to prevent its bending or flexure in use, and I further stiffen the structure vertically by the use of pipe thimbles surrounding the bolts, the ends of which abut against the inner surfaces of the end flanges of my pressed steel column guides.

Having thus given a general description of my invention, I will now, in order to make the matter more clear, refer to the annexed sheet of drawings forming part of this specification and in which like characters of reference designate like parts.

Figure 1 is a side elevation of my improved truck; Fig. 2 is a top plan of the side frame with the wheels and journal boxes removed for the sake of clearness of illustration; Fig. 3 is a vertical cross sectional elevation taken on the line III—III of Fig. 2; Fig. 4 is a side elevation of a portion of the column guide shown in Fig. 3; Fig. 5 is a vertical cross sectional elevation of the column guides illustrated in Figs. 3 and 4 on the line V—V of Fig. 6; Fig. 6 is a sectional plan taken on the line VI—VI of Fig. 4; Fig. 7 is a cross sectional plan taken on the line VII—VII of Fig. 5; and Fig. 8 is a detailed longitudinal vertical sectional elevation of the parts adjacent one of the column bolts.

Referring now to the various characters of reference on the drawings: 1 is the upper arch bar, 2 the lower arch bar, the ends of

which are turned up and abut against the ends of the upper arch bar, 3 is a reinforcing member secured to the lower arch bar by rivets countersunk on top, as shown; 4 is the lower tie bar, 5 are the journal boxes of usual construction, 6 is the spring plank shown as of pressed steel secured to the bottom arch bar and to the column guides by rivets; 7 indicates my pressed steel column guides generally, 8 are the column bolts, 9 are pipe thimbles made preferably of heavy wrought iron or steel which surround the column bolts with their ends abutting against the insides of the horizontal flanges of the truck columns in order to stiffen the structure; 10 is an inwardly extending portion of the integral column guide adapted to serve as a guide for the bolster in its up and down motion on the springs, 11 is the lower portion of the column guide which is pressed inwardly to form clearance and space for introducing the bolster into position, after which the bolster is moved upwardly into contact with the guide portions 10, 12 is the upper horizontal flange of the column guide adapted to be secured against the lower surface of the upper arch bar 1, 13 is the lower horizontal flange of the column guide adapted to be secured against the upper surface of the stiffening member 3, as illustrated; 14 is an integral projection extending diagonally inward from the body of the column guide, provided with web portions 15 and 16, which are provided with holes, as illustrated, and so located and adapted as to form a direct support for the brake beam stirrup or hanger 17, which is pivotally secured thereto by means of the bolt 18, while the usual springs are illustrated as 19 and the bolster as 20. By means of this construction I provide column guides which are integrally formed of pressed steel and of a strength sufficient to stand the stresses to which they are subjected, and of quality such that they are better than a casting or a column guide made of more pieces, my column guide and the brake hanger being formed integral.

On account of the necessary width of a truck frame of this character, the load applied thereto from the springs is transmitted to the lower central portion of the lower arch bar and would tend to bend or flex it, but my stiffener 3 is used for the purpose of strengthening the lower arch bar to prevent this.

Although I have described and illustrated my invention in considerable detail, I do not wish to be limited to the exact and specific details thereof as shown and described, but 5 may use such modifications in, substitutions for, or equivalents thereof, as are embraced within the scope of my invention, or as pointed out in the claims.

Having thus described my invention, what 10 I claim and desire to secure by Letters Patent is:—

1. An integrally formed column guide of pressed steel comprising top and bottom flanges adapted to fit within the opening of 15 a truck frame, the upper part of which extends toward the bolster to form a bolster guide, said truck column being provided

with an integral inwardly extending portion adapted to directly support a brake beam hanger pivotally secured thereto. 20

2. An integrally formed pressed steel column guide comprising upper and lower flange portions adapted to fit within the opening between the truck arch bars, the upper portion adapted to contact with the bolster and the lower portion not adapted to contact with the bolster, a pair of webs extending vertically between the arch bars, an inwardly projecting portion comprising a web and flanges, the flanges being perforated 25 and adapted to support a brake beam hanger. 30

In testimony whereof I hereunto affix my signature.

RALPH E. WILDER.
